UNITED STATES PATENT OFFICE.

THEODORE COTE AND EDWARD VICTOR COTE, OF TUPPER LAKE, NEW YORK.

HOLDING DEVICE FOR CHAIRS.

Application filed December 23, 1925. Serial No. 77,313.

This invention relates to improvements in holding devices for use upon barber chairs and the like for supporting the head rest thereon when not in use and obliterating the necessity of making room for the head rest upon a shelf each time the head rest is removed from the chair.

Another object of our invention resides in the specific construction of the device consisting of a clamp arranged upon the frame of the chair and having an outwardly extending U-shaped member thereon for receiving the leg of the head rest therein while a pair of protecting rods extending upwardly in spaced parallel relation upon the under side of the clamp for preventing the head rest from coming in contact with the seat and from accumulating any extraneous matter thereon from contacting with any portion of the chair.

With the above and other objects in view, the invention further includes the following novel features and details of construction, to be hereinafter more fully described, illustrated in the accompanying drawings and pointed out in the appended claim.

In the drawing:

Figure 1 is a side elevation of a barber chair with parts broken away and illustrating the manner in which our invention is secured upon the frame therefor.

Figure 2 is a perspective of our invention per se.

Figure 3 is a vertical sectional view taken through the invention and illustrating the manner in which the elements so forming our invention are associated with the clamp.

Referring to the drawing in detail, wherein like characters of reference denote corresponding parts, the reference character 10 indicates a barber chair of the usual and well known construction and having a downwardly extending rectangular frame 11 provided thereon while the back of the chair being constructed to receive the leg 12 of a head rest 13 thereon in accordance with the usual and well known construction of the particular type of chair.

The invention mainly resides in the provision of a substantially U-shaped clamping member 14 through one side of which is movable a wing bolt 15 and upon the inner end of the wing bolt is a swiveled head 16

which is adapted for engagement with the inner side of the frame 11 for supporting 55 the clamp 14 thereon in the manner clearly illustrated in Figure 1 of the drawing.

Extending in a like manner within the diametrically opposite side of the clamp 14 is an inwardly extending projection 17 provided upon the intermediate portion of a yoke shaped supporting member 18; the projection 17 being held against accidental displacement through the instrumentality of a jam nut 19 threaded upon and abutting 65 the corresponding outer side of the clamp 14. The leg 12 of the head rest 13 being received between the corresponding inner sides of the yoke shaped member 18 while the head rest proper being supported upon 70 the upper side of the yoke shaped member 18.

In order to prevent the inner side of the head rest 13 from contacting with the chair 10 or the frame 11 therefor we provide a pair 75 of spaced parallel upwardly extending protecting rods 20 upon the upper edge of the U-shaped clamping member 14 exteriorally of the frame 11 and which will hold the said head rest 13 in spaced relation with respect 80 to the seat 10 and frame 11 to prevent the accumulation of any extraneous matter whatsoever thereupon.

The invention is susceptible of various changes in its form, proportions and minor 85 details of construction, and the right is herein reserved to make such changes as properly fall within the scope of the appended claim.

Having thus described the invention, what 90 is claimed is:

A device of the character described including a U-shaped clamping member, a wing bolt adjustable through one side of the clamping member, a U-shaped yoke having 95 an inwardly extending threaded projection engaged with the side of the clamping member opposite the wing nut and upwardly extending spaced parallel projecting rods having their lower ends removably engaged 100 with the upper edges of the side wall of the clamp to which the yoke is attached.

In testimony whereof we affix our signatures.

THEODORE COTE.
EDWARD VICTOR COTE.
